Fig 7

Fig 8

Fig 9

Fig 10

FIG. 1 is a front elevational view of a table lighter, showing my new design;
 FIG. 2 is a side elevational view thereof;
 FIG. 3 is a rear elevational view thereof;
 FIG. 4 is an elevational view of the side opposite that shown in FIG. 2;
 FIG. 5 is a top plan view thereof;
 FIG. 6 is a bottom plan view thereof;
 FIG. 7 is a perspective view thereof;
 FIG. 8 is a top plan view of a second embodiment of my new design;
 FIG. 9 is a bottom plan view thereof; and
 FIG. 10 is a perspective view thereof.

This is a continuation of design applications Ser. No. D. 21,804 and Ser. No. D. 21,807, both filed Mar. 9, 1970 and now abandoned.

I claim:
 The ornamental design for a table lighter, substantially as shown and described.
